REVERSIBLE VANE MOTOR

Edgar Wayne Kay, Detroit, Mich., assignor to
 The Oilgear Company, Milwaukee, Wis., a corporation of Wisconsin

Application May 20, 1942, Serial No. 443,730

19 Claims. (Cl. 121—87)

This invention relates to reversible vane type motors and associated control mechanisms. More particularly, the invention relates to reversible vane type motors in which overrun of the rotor assembly may take place incident to reversal of its direction of rotation.

Motors of the type to which the invention relates in particular include a vane track that surrounds the rotor and vane assembly and is adapted to contact the radially outer ends of the vanes to guide and control their inward and outward motions as the rotor rotates. For quiet and satisfactory operation of the motor, it is practically essential that the outer ends of the vanes be urged into contact with the vane track when operation of the motor is started and that such contact be maintained continuously during its operation.

In order to provide this track-contacting and track-following action of the vanes, it is necessary to supplement the action of centrifugal force with an auxiliary force acting to urge the vanes outward, at least during the portion of their rotary travel in which they are passing through the inlet area or areas of the motor, so that the outer ends of the vanes will be held firmly in contact with the surrounding vane track and thus provide a movable resistance to the motive fluid acting upon the outer end portions of the vanes, whereby rotary motion is imparted to the rotor and driven shaft of the motor. In the vane motor of the present invention, fluid pressure means are utilized to provide this auxiliary force and this is accomplished by introducing or admitting, behind the inner ends of the vanes, fluid having a pressure sufficient to move the vanes outward and keep their outer ends in contact with the vane track while passing through the inlet area or areas.

The present invention is not concerned with the nature of the pressure fluid admitted to the inner ends of the vanes but it is preferably a differential pressure fluid. That is, the pressure of the fluid admitted behind the inner ends of the vanes is a predetermined amount higher than the pressure of the motive fluid that acts upon the outer end portions of the vane to drive the motor.

The means for providing motive fluid and differential pressure fluid form no part of the present invention. For the purpose of illustration, the accompanying drawings show that the two pressures are obtained by passing the motive fluid through a resistance valve but it is to be understood that any other suitable means may be

employed, such as an auxiliary pump which delivers enough fluid to the inner ends of the vanes to urge them outward and which discharges the remainder of its output through a resistance valve into the motive fluid supply channel.

The drive shaft, rotor and vanes are the only rotating parts of a vane type fluid motor of the character under consideration and constitutes its entire rotor assembly. These parts are relatively small and light in weight and their inertia is usually so small that, when these parts constitute the entire inertia load, they may be stopped almost instantly upon reversal of the high and low pressure fluid connections to reverse the direction of rotation of the rotor assembly. In fact, the small size and light weight of the rotating masses of vane type motors of this class are among the most important and distinctive features of such motors and make possible exceedingly rapid acceleration, deceleration and reversal.

However, these motors are frequently employed to drive relatively large inertia loads which require either an extremely high pressure of the motive fluid to instantly stop their rotation or a relatively longer time for deceleration. In most instances it is not practical to instantly stop the rotation of large inertia loads when rotating at high speeds because of the excessively high pressure required to effect stoppage and it is customary to decelerate the load as rapidly as can be accomplished within certain reasonable pressure limits or as may be necessary for the safe operation of the driven device, and during such deceleration the rotor assembly tends to overrun, i. e., tends to continue momentarily to rotate in the direction in which it was rotating just prior to reversal of the motor's high and low pressure fluid connections. During such overrun the device functions as a vane type pump which is driven by the inertia load, with the speed of its rotor assembly progressively decreasing as deceleration takes place so that there is a corresponding decrease in the centrifugal force available to move the vanes outward into contact with the vane track.

For quiet and satisfactory operation during periods of overrun, it is necessary to provide a force to urge the vanes outward as they pass through the inlet areas which are at that time the low pressure areas due to the motor functioning as a pump. Unless such auxiliary force is provided, the result will be noisy and unsatisfactory operation comparable to that encountered in any vane type pump if the vanes do

not move out properly as they pass through the intake areas and in which the vanes are working against a substantial pressure.

Satisfactory operation of a reversible vane type fluid motor in which overrun of the rotor assembly occurs thus requires a provision of an auxiliary force to urge the vanes outward into contact with the vane track during the time that the outer ends thereof are passing through the inlet areas and this is the case irrespective of whether the inlet areas are the high pressure areas, as is the case during normal or non-reversing operation of the motor, or whether such inlet areas are the low pressure areas as is the case during overrun of the rotor assembly through the period of deceleration incident to reversal.

It has heretofore been proposed to supply differential high pressure fluid to the inner ends of all of the vanes continuously but, during the periods between reversals, such an arrangement causes the outer end of each vane as it passes through the low pressure area to be urged against the vane track by a very large force which greatly reduces the efficiency of the motor and causes undue wear of the vane track and the outer end of the vane.

The present invention has as an object to provide a vane type motor which will operate quietly and efficiently both during reversal and during normal operation.

Another object is to provide a vane type motor capable of being reversed at a rapid rate, that is, a motor capable of operating under conditions which require successive reversals of the motor at extremely brief intervals.

Another object is to provide a vane type motor with an automatic control mechanism which is positive and precise in operation.

Other objects and advantages will appear from the description hereinafter given of a vane type fluid motor and associated control mechanism in which the invention is embodied.

Vane type motors are at present ordinarily energized by motive liquid, such as oil, and the present invention will be described as embodied in a constant displacement hydraulic motor and associated control mechanism but it is to be understood that the invention is equally applicable to elastic fluid motors and to variable displacement motors.

The invention is exemplified by the vane type motor and associated control mechanism shown in part schematically in the accompanying drawings in which the views are as follows:

Fig. 1 is a view, partly in side elevation and partly in vertical longitudinal section, of a vane type motor to which the invention has been applied.

Fig. 2 is a transverse section taken along the line 2-2 of Fig. 1.

Fig. 3 is a fragmentary longitudinal section, partly in full, taken along the irregular line 3-3 of Figs. 2 and 4.

Fig. 4 is a transverse section taken on the line 4-4 of Fig. 1.

Fig. 5 is a view of the inner face of one of the two cheek plates between which the rotor rotates.

Fig. 6 is a diagrammatic view showing the hydraulic circuits of the motor and its control mechanism.

Figs. 7, 8 and 9 are views showing the piston of the control valve in positions different from that shown in Fig. 6.

The motor has its mechanism arranged within

a casing 10 having a circular chamber 11 formed therein and closed by a removable end head 12 which is attached to casing 10 by bolts 13. Chamber 11 has two cheek plates 14 and 15 fitted therein and spaced apart by a spacer ring 16 the inner peripheral surface of which is approximately elliptical and forms a vane track 17, the cheek plates and spacer ring being firmly clamped together within chamber 11 by head 12 and bolts 13.

A cylindrical rotor 18 is closely fitted for rotation between the two cheek plates and provided with a plurality of radial vane slots 19 in each of which a vane 20 is slidably fitted and has its outer end in contact with vane track 17. Rotor 18 is splined upon the inner end of a drive shaft 21 which extends outward through casing 10 and is rotatably supported by suitable bearings arranged therein, the splined connection being of such a nature that rotor 18 can adjust itself between the cheek plates and thereby permit it to be closely fitted therebetween.

As previously explained, vane track 17 is approximately elliptical and has been shown as having its horizontal diameter but slightly greater than the diameter of rotor 18 and its vertical diameter considerably greater than the diameter of rotor 18 to thereby leave spaces between the periphery of rotor 18 and the upper and lower portions of vane track 17. The division between these two spaces is effected by cooperation of rotor 18 and the outer ends of vanes 20 with vane track 17 at the region of the vane track's least diameter, and these regions are concentric with rotor 18 to provide arcs 22 which are generally known as "sealing arcs" and are of a length at least as great as the angular distance between adjacent vanes 20.

The two spaces between rotor 18 and vane track 17 are each divided into interchangeable inlet and outlet areas with a working chamber therebetween. The inlet area and the outlet area in one of the spaces are diametrically opposed, respectively, to the inlet area and the outlet area in the other space in order that rotor 18 may be hydrostatically balanced in respect to the radial forces acting thereon. Division between the inlet areas and the outlet areas is effected by vanes 20 engaging track 17 at the regions of its greatest diameter and these regions are concentric with rotor 18 to provide arcs 23 which are generally known as "working arcs" and are of a length at least as great as the angular distance between adjacent vanes 20.

Rotor 18 and vanes 20 form substantially fluid tight joints with the inner faces of cheek plates 14 and 15 so that, when motive liquid is supplied to the inlet areas, it will act upon the exposed portions of those vanes in contact with working arcs 23 and cause those vanes to rotate rotor 18 and shaft 21 toward the outlet areas into which the liquid trapped between adjacent vanes is discharged as the vanes are moved inward by passing along vane track 17 toward sealing arcs 22.

As best shown in Fig. 5, cheek plates 14 and 15 are each provided with a pair of diametrically opposed ports 28 and a pair of diametrically opposed ports 29 which communicate with the interchangeable inlet and outlet areas as shown in Fig. 2, the ports in one cheek plate being arranged axially opposite the corresponding ports in the other cheek plate as shown in Fig. 3. One pair of ports in cheek plate 15 is adapted to admit motive liquid to the inlet areas and the other pair of ports in cheek plate 15 is adapted

73

to permit the discharge of liquid from the outlet areas but the ports in cheek plate 14 function simply as balance ports to hydrostatically balance rotor 18 in an axial direction in respect to the pressure exerted thereon by the motive liquid.

The motor is adapted to have motive liquid supplied thereto through one and to have liquid discharged therefrom through the other of two pipes 30 and 31 which are attached to casing 10 and communicate, respectively, with two annular channels 32 and 33 (Fig. 4) formed therein. Channel 32 communicates through two short passages 34 with the two ports 28 in cheek plate 15, and channel 33 communicates through two short passages 35 with the two ports 29 in cheek plate 15.

When motive liquid is supplied through pipe 30, it will flow through channel 32, passages 34 and ports 28, act upon the exposed end portions of the vanes 20 in contact with working arcs 23 and cause rotor 18 to rotate in a counterclockwise direction in respect to Fig. 2, and the liquid carried across arcs 23 by the vanes will be discharged through ports 29, passages 35 and channel 33 into pipe 31 which is at that time the discharge pipe.

When motive liquid is supplied through pipe 31, it will flow through channel 33, passages 35 and ports 29, act upon the exposed portions of the vanes 20 in contact with working arcs 23 and cause rotor 18 to rotate in a clockwise direction in respect to Fig. 2, and the liquid carried across arcs 23 by the vanes will be discharged through ports 28, passages 34 and channel 32 into pipe 30 which is at that time the discharge pipe.

Efficient operation of the motor requires that the vanes be held in contact with the vane track at all times. Therefore, the vanes must be moved progressively outward as they pass through the inlet areas and be moved progressively inward by the vane track as they pass through the outlet areas. In order to obtain efficient operation of the motor, the inner end of each vane slot 19 registers successively with a plurality of vane slot ports which are formed in cheek plates 14 and 15 to admit pressure liquid behind the inner ends of the vanes the outer ends of which are passing through the inlet areas and across the sealing and working arcs and to permit the discharge of liquid from the inner ends of the slots 19 containing the vanes which are being moved inward by the vane track.

As shown in Fig. 5, each of cheek plates 14 and 15 has formed therein a pair of diametrically opposed short vane slot ports 36, a pair of diametrically opposed short vane slot ports 37, a pair of diametrically opposed vane slot ports 38 and a pair of diametrically opposed vane slot ports 39. Vane slot ports 36 are spaced radially inward from working arcs 23, vane slot ports 37 are spaced radially inward from sealing arcs 22, vane slot ports 38 are spaced radially inward from main ports 28, and vane slot ports 39 are spaced radially inward from main ports 29. The vane slot ports in cheek plate 14 extend completely therethrough in order that they may be connected to an external circuit but the vane slot ports in cheek plate 15 are simply grooves formed in its inner face and function as balance ports to hydrostatically balance rotor 18 in respect to the pressures prevailing in the vane slot ports in cheek plate 14.

Vane slot ports 36 and 37 are each connected by a passage 40 (Fig. 1) to a channel 41 which extends through end head 12 into communication

with a valve block 42 which has been shown attached to end head 12. Vane slot ports 38 are each connected by a passage 43 (Fig. 3) to an annular passage 44 which is formed in end head

5 12 and connected by a channel 45 to valve block 42. Vane slot ports 39 are each connected by a passage 46 (Fig. 3) to an annular passage 47 which is formed in end head 12 and connected by a channel 48 to valve block 42.

10 Any suitable means may be employed for directing motive liquid to and exhausting liquid from the motor, for reversing the direction of liquid flow to thereby effect reversal of the motor, and for directing high pressure liquid to 15 the vane slot ports selectively but, for the purpose of illustration, Fig. 6 schematically shows the motor connected to a source of pressure liquid and to exhaust through a reversing valve, the high pressure liquid supplied directly from the 20 pressure source and a resistance valve connected between the reversing valve and the source to cause a drop in the pressure of the motive liquid supplied to the inlet areas of the motor.

As shown, pipes 30 and 31 are connected to 25 opposite sides of a reversing valve 55 which in the position shown connects pipe 30 to an exhaust pipe 56 and connects pipe 31 to a pressure pipe 57 and which when shifted will connect pipe 30 to pressure pipe 57 and pipe 31 to exhaust pipe 56. Pipe 57 is connected through a resistance valve 58 to a supply pipe 59 which is connected to a source of pressure liquid such as a pump not shown, and high pressure liquid is supplied to the vane slot ports selectively through 30 a channel 60 which is connected to supply pipe 59. Resistance valve 58 causes a drop in pressure between channels 59 and 57 so that the pressure prevailing in the vane slot ports connected to channel 60 exceeds the pressure of the motive liquid delivered to the inlet areas of the motor by an amount equal to the pressure required to open resistance valve 58 which ordinarily opens at a very low pressure.

The flow of liquid to and from the vane slot 40 ports is controlled by a valve 65 which has been shown in Fig. 1 as being attached to valve block 42 and which is shown in detail but somewhat schematically in Figs. 6 to 9. As shown, control valve 65 is symmetrical about its transverse center line and has a valve member 66 arranged in a valve casing 67 and provided with three spaced apart heads or pistons 68, 69 and 70 to control communication between five annular grooves or 45 ports 71, 72, 73, 74 and 75 formed in the bore of casing 67.

Valve casing 67 has two cylinders 76 and 77 arranged upon opposite ends thereof and communicating with ports 74 and 75 respectively. Cylinders 76 and 77 have pistons 78 and 79 fitted 50 therein, respectively, and urged toward valve member 66 by springs 80 and 81 respectively. Pistons 78 and 79 have chokes 82 and 83 arranged therein, respectively, to permit liquid to flow at a limited rate from the outer end to the inner end of each cylinder when the piston therein is moved by valve member 66 as will presently be explained.

The ports and cylinders of valve 65 are connected to the several ports in the motor by a plurality of passages, check valves and resistance valves as shown schematically in Fig. 6. In practice, these valves and passages are arranged in valve block 42 which has not been illustrated in detail for the reason that its exact construction forms no part of the present invention.

Ports 74 and 75 in valve casing 67 are connected to opposite sides of the main hydraulic circuit by channels 84 and 85 which have been shown in Fig. 6 as being connected, respectively, to pipes 30 and 31 but which in practice extend through end head 12 into communication with ports 28 and 29. Channels 86 and 87 are connected, respectively, to cylinders 76 and 77 by channels 88 and 89 having check valves 90 and 91 arranged therein, respectively, to permit liquid to flow freely from the main hydraulic circuit to cylinders 76 and 77 but to prevent it escaping therefrom except through chokes 82 and 83.

Channel 41, which is connected by passages 40 to vane slot ports 36 and 37, extend through valve block 42 into communication with port 71 with which channel 66 also communicates so that vane slot ports 36 and 37 are continuously supplied with differential pressure liquid, that is, with liquid at a pressure which exceeds the pressure of the motive liquid by an amount equal to the resistance of resistance valve 58.

Passage 45, which communicates through passages 44 and 43 with valve slot ports 38, is connected through a check valve 92 and a resistance valve 91 to a channel 92 which communicates with port 72. Passage 48, which communicates through passages 47 and 46 with valve slot ports 39, is connected through a check valve 93 and a resistance valve 94 to a channel 93 which communicates with port 73. Check valves 90 and 91 permit liquid to flow freely from valve 66 to vane slot ports 38 and 39, and resistance valves 91 and 94 offer a low resistance to the discharge of liquid from vane slot ports 38 and 39.

Channels 92 and 93 are connected, respectively, by check valves 96 and 97 to channel 41 and they are also connected, respectively, by check valves 98 and 99 to channels 84 and 85 so that liquid can escape from one and liquid may be supplied to the other of the two pairs of vane slot ports 38 and 39 when valve member 66 is in either one of its two positions in which it blocks one or the other of ports 72 and 73.

Operation

With the parts in the positions shown in Fig. 6 and pressure liquid being supplied to pipe 59, the areas around ports 29 will be inlet areas and the areas around ports 28 will be the outlet areas. Liquid will flow from pipe 59 through resistance valve 58, pipe 57, reversing valve 55, pipe 31, channel 33, passages 35 and ports 29 to the inlet areas, act upon the exposed portions of the vanes 20 in contact with working arcs 23 and cause rotor 18 to rotate in a clockwise direction in respect to Fig. 2. As the vanes pass beyond areas 23, the liquid trapped between adjacent vanes will be discharged into the outlet areas and will flow therefrom through ports 28, passages 34, channel 32, pipe 30 and reversing valve 55 into exhaust pipe 56.

At the same time, differential pressure will extend from pipe 59 through channel 60, valve 65, channel 95, check valve 93 and passages 48, 47 and 46 to vane slot ports 39 and from valve 65 through channel 41 and passages 40 to vane slot ports 36 and 37. The vanes passing through the inlet areas will be moved progressively outward and held firmly in contact with track 17 by the differential pressure in vane slot ports 39 and the vanes passing across sealing arcs 22 and working arcs 23 will be held firmly in contact therewith by the differential pressure in vane slot ports 36 and 37.

The vanes 20 passing through the outlet areas will be moved progressively inward by vane track 17 and will expel liquid from the inner ends of their vane slots 19 through vane slot ports 38, 5 passages 43, 44 and 45, resistance valve 91, channel 92, valve 65 and channel 34 into the discharge side of the motor circuit.

Resistance valve 91 offers a low resistance to the discharge of liquid from vane slot ports 38 and 10 thereby prevents those vanes which are passing across ports 28 from falling to the bottoms of their slots when the motor is operating at such a slow speed that there is insufficient centrifugal 15 force to hold those vanes in contact with the vane track. Resistance valve 94 performs the same function when rotor 18 is rotating in a counter-clockwise direction.

When the fluid connections are reversed as by shifting valve 55 to connect pipe 30 to pipe 51 20 and pipe 31 to pipe 56, liquid will tend to flow through pipe 30, channel 32 and passages 34 to ports 28 and tend to drive the motor in the opposite direction but, if the motor is connected to an inertia load as is usually the case, the inertia 25 of the load will cause the motor to overrun. That is, the load will drive the motor and cause it to continue to rotate in the same direction which will cause the motor to function as a pump in that it will draw liquid through ports 29 and discharge liquid into ports 28, thereby causing the pressure in the areas around ports 28 to rise to a maximum as determined, for example, by a relief valve such as the relief valves with which hydraulic transmissions are almost invariably provided.

The high pressure in the areas around ports 28 30 will act upon the exposed end portions of the vanes 20 in contact with working arcs 23 and quickly decelerate rotor 18 to zero speed and then 35 start it rotating in the opposite direction, thereby reversing the motor.

During the period between the reversal of the fluid connections and the reversal of the motor, ports 29 continue to be inlet ports but the pressure 40 therein is very low or negative, and ports 28 continue to be outlet ports but the pressure 45 therein is very high. Therefore, if the pressures in the vane slot ports were reversed simultaneously with the reversal of the pressures in the inlet and 50 outlet areas, no liquid would be supplied to vane slot ports 39 to move outward the vanes passing through the inlet areas during that period.

However, as soon as the fluid connections are 55 reversed, liquid will flow through channel 64 to port 74 and shift valve member 66 toward the right at high speed until it strikes piston 79, at which time it is in the position shown in Fig. 8, and then it will continue to move toward the right at a limited rate as determined by choke 83 60 until it reaches its extreme position as shown in Fig. 7. At the same time, spring 80 will move piston 78 toward the right into contact with the inner end of cylinder 76, and piston 78 will draw liquid into the outer end of cylinder 76 through channel 86, check valve 88 and channel 84.

As valve member 66 approaches its central position, piston 69 thereon blocks communication between port 72 and port 74 and piston 68 opens communication between port 72 and port 71, thereby directing differential pressure liquid through channel 92, check valve 90 and passages 65, 44 and 43 to vane slot ports 38, and communication between port 73 and port 71 will not be blocked until after valve member 66 has 70 passed beyond its central position. Consequently,

during the period that valve member 66 is at and near its central position, all of the vane slot ports are supplied with differential pressure liquid which urges all of the vanes into firm engagement with the vane track during at least the greater part of the time required to effect reversal of the motor.

If the movement of valve member 66 could be so timed that ports 72 and 73 would both remain in communication with port 71 during exactly the same period of time that would be required to effect reversal of the motor, it would only be necessary to so construct and adjust valve 65 that valve member 66 would move quickly from one extreme position to its central position, pause at or near its central position for the required length of time and then move quickly to its other extreme position.

However, the time required to effect reversal of the motor will vary in accordance with variations in several factors including variations in the size and speed of the load driven by the motor. Therefore, if valve 65 operated in the above manner and the check valves and the resistance valves in valve block 42 were omitted, the motor would not operate satisfactorily for the following reasons:

If the valve were adjusted to maintain differential pressure under all of the vanes during a period equal to the longest time required to effect reversal of the motor and the motor reversed in a shorter time, the differential pressure would cause the vanes passing through the low pressure areas to exert very high forces against the vane track between the time the motor reversed and the end of the period, thereby reducing the efficiency of the motor and causing undue wear of the vane track and the outer ends of the vanes. If the valve were adjusted to maintain differential pressure under all of the vanes during a period equal to the shortest time required to effect reversal of the motor and a longer time were required to effect reversal of the motor, the vanes passing through the low pressure areas after the end of that period would depend solely upon centrifugal force to hold them in contact with the vane track but, since rotor 18 at that time would be rotating at slow speed, centrifugal force would be insufficient and the vanes would drop to the bottoms of their slots and remain there until the inner ends of those slots registered successively with vane slot ports 37 and then the differential pressure therein would force the vanes outward at high speed and cause them to strike the vane track with considerable force, thereby creating objectionable noise and causing damage to the vanes and the vane track. However, valve 65 and the valves in valve block 42 cooperate to effect quiet and efficient operation of the motor.

As valve member 66 moves from the position shown in Fig. 6 toward its central position, it momentarily blocks port 72 in the same manner that it blocks port 73 after it has passed beyond its central position as shown in Fig. 9. When port 72 is thus momentarily blocked, rotor 18 is still rotating in a clockwise direction at high speed, the vanes passing across ports 29 are being moved outward by centrifugal force and the vanes passing across ports 28 are being forced inward by the vane track. The outward moving vanes will draw liquid into their vane slots from the hydraulic circuit through channel 85, check valve 99, channel 95, check valve 93, passages 48, 47 and 46 and vane slot ports 39. The inward

moving vanes are exhausting liquid into vane slot ports 38 so that, if valve member 66 blocked the only channel of escape for this liquid, a very high pressure would be momentarily raised in vane slot ports 38 and the channels connected thereto. However, check valve 96 is provided so that the liquid discharged by the vanes into vane slot ports 38 at such time may flow therefrom through passages 43, 44 and 45, resistance valve 94, channel 92 and check valve 96 into channel 41. The functions performed by check valves 96 and 99 when rotor 18 is rotating in a clockwise direction is performed by check valves 97 and 98 when rotor 18 is rotating in a counterclockwise direction and the fluid connections are reversed to effect reversal of the motor.

After valve member 66 strikes piston 79 and is decelerated thereby at and near its central position so that all of the vanes are held in contact with the vane track by differential pressure, it continues to move toward the right at a limited rate as explained above and during this movement it blocks port 73 as shown in Fig. 9.

If reversal has not taken place so that rotor 18 is still rotating in a clockwise direction when port 73 is blocked, the vanes passing across ports 28 are being firmly held against the vane track by differential pressure for the reason that port 72 at this time is open to port 71. If rotor 18 is rotating at a high enough speed, centrifugal force causes the vanes passing across ports 29 to move outward into contact with the vane track and to draw liquid into their vane slots from the low pressure side of the hydraulic circuit through channel 85, check valve 99, channel 95, check valve 93, passages 48, 47 and 46 and vane slot ports 39. If rotor 18 is rotating at a low speed, the vanes passing across ports 28 will be moved outward against the vane track by liquid flowing from vane slot ports 36 and 37 to vane slot ports 39 through the lubricating film of liquid between rotor 18 and each of the cheek plates, it being understood that only an extremely small amount of liquid is required for this purpose due to the slow speed of rotor 18 and that pressure can be raised in ports 39 at this time due to port 73 being blocked. Liquid can flow at other times through the lubricating film from vane slot ports 36 and 37 to the vane slot ports 38 or 39 containing low pressure but a high pressure cannot be created therein unless port 72 or port 73 is blocked or open to port 71.

If reversal has taken place so that rotor 18 is rotating in a counterclockwise direction when port 73 is blocked, the vanes passing across ports 28 are being moved outward into engagement with the vane track by differential pressure due to the fact that port 72 is at this time open to port 71, and the vanes passing across ports 29 are being moved inward by the vane track and are discharging liquid from their vane slots through ports 39, passages 46, 47 and 48, resistance valve 94, channel 95 and check valve 97 into channel 41.

Valve member 66 continues to move toward the right until it reaches the position shown in Fig. 7 at which time port 72 continues to communicate with port 71 and port 73 is open to port 75 so that the vanes passing across ports 28 are being moved outward by differential pressure into engagement with the vane track and the vanes passing across port 29 are being moved inward by the vane track and are discharging liquid from their vane slots through vane slot ports 39, passages 46, 47 and 48, resistance valve 94, chan-

nel 95, valve 65 and channel 85 into the low pressure side of the hydraulic circuit.

When the fluid connections are again reversed, the mechanism will operate as explained above, but in the opposite direction to effect reversal of the motor and to maintain quiet and efficient operation thereof.

The operation has been explained step by step and valve member 66 has been referred to as being in various positions but it is to be understood that the control mechanism operates continuously during reversal and that the time required for valve member 66 to move from one to the other of its extreme positions is very short, the control mechanism being used principally in connection with a fast reversing motor and sixty reversals per minute having been readily obtained.

While only a single embodiment of the invention has been illustrated and described, it is to be understood that the motor and associated control mechanism may be modified in various ways without departing from the scope of the invention which is hereby claimed as follows:

1. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, means for connecting the inner ends of said vanes with said channel during the time the outer ends of said vanes are passing through the inlet area and for connecting the inner ends of said vanes to exhaust during the time the outer ends of said vanes are passing through the outlet area, and means for resisting the discharge of fluid from the inner ends of those vanes the outer ends of which are passing through the outlet area.

2. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, means responsive to reversal of the relative pressures in said inlet and outlet areas for connecting the inner ends of said vanes with said channel during the time the outer ends of said vanes are passing through the inlet area and for connecting the inner ends of said vanes to exhaust during the time the outer ends of said vanes are passing through the outlet area, and means for resisting the discharge of fluid from the inner ends of those vanes

the outer ends of which are passing through the outlet area.

3. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve for connecting the inner ends of said vanes with said channel during the time the outer ends of said vanes are passing through the inlet area and for connecting the inner ends of said vanes to exhaust during the time the outer ends of said vanes are passing through the outlet area, and means providing during movement of said valve a passage for the discharge of fluid from the inner ends of those vanes the outer ends of which are passing through the outlet area.

4. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve for connecting the inner ends of said vanes with said channel during the time the outer ends of said vanes are passing through the inlet area and for connecting the inner ends of said vanes to exhaust during the time the outer ends of said vanes are passing through the outlet area, and means providing during movement of said valve a passage for the discharge of fluid from the inner ends of those vanes the outer ends of which are passing through the outlet area.

5. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve operable in response to reversal of the relative pressures in said inlet and outlet areas for connecting the inner ends of said vanes with said channel during the time the outer ends of

of said vanes are passing through the inlet area and for connecting the inner ends of said vanes to exhaust during the time the outer ends of said vanes are passing through the outlet area, and means providing during movement of said valve a passage for the discharge of fluid from the inner ends of those vanes the outer ends of which are passing through the outlet area.

6. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve operable in response to reversal of the relative pressures in said inlet and outlet areas for connecting the inner ends of said vanes with said channel during the time the outer ends of said vanes are passing through the inlet area and for connecting the inner ends of said vanes to exhaust during the time the outer ends of said vanes are passing through the outlet area, means for resisting the discharge of fluid from the inner ends of those vanes the outer ends of which are passing through the outlet area, and means providing during movement of said valve a passage for the discharge of fluid from the inner ends of those vanes the outer ends of which are passing through the outlet area.

7. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to exhaust during the time the outer ends of said vanes are passing through the outlet area, and a channel connecting each of said ports to said valve and having a check valve and a resistance valve connected therein and opening in opposite directions to provide a free flow of fluid to said ports and to resist the discharge of fluid therefrom.

8. In a reversible vane type fluid motor, a rotor having vanes slidable therein, a track for guiding said vanes in their inward and outward movements, means for enclosing said rotor and track and providing interchangeable fluid inlet and

outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to exhaust during the time the outer ends of said vanes are passing through the outlet area, and a check valve connected between each of said ports and said channel to prevent fluid from being trapped in said ports during movement of said first valve in either direction.

9. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to exhaust during the time the outer ends of said vanes are passing through the outlet area, and means for supplying fluid to each of said ports from one of said inlet and outlet areas during movement of said valve including a check valve to prevent flow of fluid in the opposite direction.

55 to prevent flow of fluid in the opposite direction.

10. In a reversible vane type fluid motor, a rotor having vanes slidably therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports

and shiftable to connect the inner ends of said vanes with said channel during the time the outer ends of said vanes are passing through the inlet area and for connecting the inner ends of said vanes to exhaust during the time the outer ends of said vanes are passing through the outlet area, a second channel connecting each of said ports to said valve and having a check valve and a resistance valve connected therein and opening in opposite directions to provide a free flow of fluid to said ports and to resist the discharge of fluid therefrom, check valves connected between said ports and said first channel to prevent fluid from being trapped in said ports during movement of said valve in either direction.

11. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to exhaust during the time the outer ends of said vanes are passing through the outlet area, a channel connecting each of said ports to said valve and having a check valve and a resistance valve connected therein and opening in opposite directions to provide a free flow of fluid to said ports and to resist the discharge of fluid therefrom, and means for supplying fluid to each of said ports from one of said inlet and outlet areas during movement of said valve including a check valve to prevent flow of fluid in the opposite direction.

12. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to

exhaust during the time the outer ends of said vanes are passing through the outlet area, a second channel connecting each of said ports to said valve and having a check valve and a resistance valve connected therein and opening in opposite directions to provide a free flow of fluid to said ports and to resist the discharge of fluid therefrom, check valves connected between said ports and said first channel to prevent fluid from being trapped in said ports during movement of said valve in either direction, and means for supplying fluid to each of said ports from one of said inlet and outlet areas during movement of said valve including a check valve to prevent flow of fluid in the opposite direction.

13. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area and for connecting the inner ends of said vanes to exhaust during the time the outer ends of said vanes are passing through the outlet area, means for connecting each of said ports to said valve including a check valve and a resistance valve which open in opposite directions to provide a free flow of fluid to each port and to resist the discharge of fluid therefrom, and a check valve connected between said channel and each of said connecting means at a point between said resistance valve and said first valve to provide during movement of said first valve a path for the discharge of fluid from the port spaced inward from an outlet area.

14. In a reversible vane type fluid motor, a rotor having vanes slidable therein, a track for guiding said vanes in their inward and outward movements, means for enclosing said rotor and track and providing interchangeable fluid inlet and outlet areas and also providing vane slot ports spaced inward from said inlet and outlet areas respectively to register with the inner ends of said vanes as the outer ends thereof pass through said areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a first valve for controlling said ports and shiftable to connect the inner ends of said vanes with said channel during the time the outer ends of said vanes are passing through the inlet area

and for connecting the inner ends of said vanes to exhaust during the time the outer ends of said vanes are passing through the outlet area, means for connecting each of said ports to said valve including a check valve and a resistance valve which open in opposite directions to provide a free flow of fluid to each port and to resist the discharge of fluid therefrom, a check valve connected between said channel and each of said connecting means at a point between said resistance valve and said first valve to provide a path for the discharge of fluid from a port during movement of said first valve, and a check valve connected between each of said areas and the port spaced inward therefrom to provide a path for free flow of fluid from said area to said port during movement of said first valve.

15. In a reversible vane type hydraulic motor, a rotor having vanes slidable therein, a track for guiding said vanes in their inward and outward movements, means for enclosing said rotor and track and providing interchangeable inlet and outlet areas and also providing vane slot ports spaced inward from said inlet and outlet areas respectively to register with the inner ends of said vanes as the outer ends thereof pass through said areas, means for supplying motive liquid to said motor including means for connecting said areas to opposite sides of a hydraulic circuit having means for reversing the flow therein to thereby make either area the inlet area, a channel for supplying to said motor liquid at a pressure higher than the pressure of said motive liquid, means for connecting said ports to said channel and to exhaust alternately including a valve having a plunger which in either of its extreme positions connects one port to said channel and the other port to exhaust and which in an intermediate position connects both ports to said channel, cylinders substantially larger than said plunger communicating with said valve at opposite ends thereof and forming therewith shoulders which are spaced apart a distance equal to the length of said plunger, a piston fitted in each cylinder, springs for urging said pistons against said shoulders, passages for supplying liquid to said cylinders, check valves in said passages to prevent the discharge of liquid therethrough from said cylinders, means responsive to operation of said flow reversing means for directing motive liquid to one end or the other of said valve to move said plunger rapidly until it engages the piston at the opposite end of said valve and is thereby substantially stopped in its intermediate position, and means providing a restricted passage for the escape of liquid from each cylinder so that said motive liquid can move said plunger only at a limited rate from its intermediate position to an extreme position.

16. In a reversible vane type hydraulic motor, a rotor having vanes slidable therein, a track for guiding said vanes in their inward and outward movements, means for enclosing said rotor and track and providing interchangeable inlet and outlet areas and also providing vane slot ports spaced inward from said inlet and outlet areas respectively to register with the inner ends of said vanes as the outer ends thereof pass through said areas, means for supplying motive liquid to said motor including means for connecting said areas to opposite sides of a hydraulic circuit having means for reversing the flow therein to thereby make either area the inlet area, a channel for supplying to said motor liquid at a

pressure higher than the pressure of said motive liquid, means for connecting said ports to said channel and to exhaust alternately including a valve having a plunger which in either of its extreme positions connects one port to said channel and the other port to exhaust and which in an intermediate position connects both ports to said channel, cylinders substantially larger than said plunger communicating with said valve at opposite ends thereof and forming therewith shoulders which are spaced apart a distance equal to the length of said plunger, a piston fitted in each cylinder, springs for urging said pistons against said shoulders, passages for supplying liquid to said cylinders, check valves in said passages to prevent the discharge of liquid therethrough from said cylinders, means responsive to operation of said flow reversing means for directing motive liquid to one end or the other of said valve to move said plunger rapidly until it engages the piston at the opposite end of said valve and is thereby substantially stopped in its intermediate position, and means providing a restricted passage for the escape of liquid from each cylinder so that said motive liquid can move said plunger only at a limited rate from its intermediate position to an extreme position.

17. In a reversible vane type hydraulic motor, a rotor having vanes slidable therein, a track for guiding said vanes in their inward and outward movements, means for enclosing said rotor and track and providing interchangeable inlet and outlet areas and also providing vane slot ports spaced inward from said inlet and outlet areas respectively to register with the inner ends of said vanes as the outer ends thereof pass through said areas, means for supplying motive liquid to said motor including means for connecting said areas to opposite sides of a hydraulic circuit having means for reversing the flow therein to thereby make either area the inlet area, a channel for supplying to said motor liquid at a pressure higher than the pressure of said motive liquid, means for connecting said ports to said channel and to exhaust alternately including a valve having a plunger which in either of its extreme positions connects one port to said channel and the other port to exhaust and which in an intermediate position connects both ports to said channel, cylinders substantially larger than said plunger communicating with said valve at opposite ends thereof and forming therewith shoulders which are spaced apart a distance equal to the length of said plunger, a piston fitted in each cylinder, springs for urging said pistons against said shoulders, passages for supplying liquid to said cylinders, check valves in said passages to prevent the discharge of liquid therethrough from said cylinders, means responsive to reversal of flow in said circuit for directing motive liquid to one end or the other of said valve to move said plunger rapidly until it engages the piston at the opposite end of said valve and is thereby substantially stopped in its intermediate position, means providing a restricted passage for the escape of liquid from each cylinder so that said motive liquid can move said plunger only at a limited rate from its intermediate position to an extreme position, means providing a low resistance to the discharge of liquid from each port and free flow thereto, and

a plurality of check valves connecting said last mentioned means to said channel and to said circuit for providing one way flow of liquid to or from said ports during movement of said plunger between an intermediate position and either of its extreme positions.

18. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve movable from one to the other of two extreme positions in each of which it connects the inner ends of said vanes with said channel during the time the outer ends of said vanes are passing through the area which is at that time the inlet area and connects the inner ends of said vanes to exhaust during the time the outer ends of said vanes are passing through the area which is at that time the outlet area, and means responsive to reversal of flow in said circuit for moving said valve quickly from one extreme position to a position intermediate its two extreme positions and thereafter moving it slowly to its other extreme position.

19. In a reversible vane type fluid motor, a rotor having vanes slidable therein, a track for guiding said vanes in their inward and outward movements, means for enclosing said rotor and track and providing interchangeable fluid inlet and outlet areas, means in communication with said areas for connecting said motor to a source of motive fluid and to exhaust and forming therewith a fluid circuit, said circuit including means for reversing the flow therein to thereby direct fluid to either of said areas to make it the inlet area and to direct fluid from the other area to exhaust to make said other area the outlet area, a channel for supplying to said motor fluid at a pressure higher than the pressure of said motive fluid, a valve movable from one to the other of two extreme positions in each of which it connects the inner ends of said vanes with said channel during the time the outer ends of said vanes are passing through the area which is at that time the inlet area and connects the inner ends of said vanes to exhaust during the time the outer ends of said vanes are passing through the area which is at that time the outlet area, means responsive to reversal of flow in said circuit for shifting said valve at high speed from one extreme position toward its other extreme position, and dashpot means engageable by said valve intermediate its two extreme positions to decelerate said valve and thereby enable said valve to move from one extreme position to an intermediate position at high speed and to then move to its other extreme position at a slow speed.
